INVENTOR

UNITED STATES PATENT OFFICE.

LEON GSCHWIND, OF YOUNGSTOWN, OHIO.

GRAVE VAULT.

Application filed August 28, 1925. Serial No. 53,074.

This invention relates to improvements in grave vaults.

The main object of this invention is to provide an improved grave vault which may be readily sealed against the entrance of water.

A further object is to provide an improved grave vault in which the parts are economical to produce and easily handled and placed in the grave.

Objects pertaining to details and economies of my invention will definitely appear from the detailed description to follow.

I accomplish the objects of my invention by the devices and means described in the following specification. The invention is clearly defined and pointed out in the claims.

A structure embodying the features of my invention is clearly illustrated in the accompanying drawing forming a part of this application, in which:

Fig. I is a side view of my improved grave vault in assembled relation.

Fig. II is a transverse section on a line corresponding to line 2—2 of Figs. I and IV.

Fig. III is a detail section on a line corresponding to line 3—3 of Fig. I showing details of the fastening means.

Fig. IV is a plan view of the base.

In the drawing similar numerals of reference indicate similar parts in all of the views and the sectional views are taken fastening in the direction of the little arrows at the ends of the section lines.

Referring to the drawing, my improved grave vault comprises a cast iron base 1 having a flange 2 of substantial width disposed in spaced relation to the edges of the base. The side portions of this flange are connected by the cross pieces 3 thereby providing a casket pedestal. The flange also serves as a reinforcing element for the base.

The body designated generally by the numeral 4 is also formed of cast iron and comprises integral top, side and end walls. The top is reinforced by the central longitudinal ribs 5 while the sides and ends have vertical ribs 6 merging into this top rib 5. At the edges of the side and end walls is a reinforcing rib 7 into which the vertical ribs also merge. The body is adapted to rest upon the base at the outside of the flange 2 thereof. The body is provided with a pair of hand holds 8.

Adjacent its side edges the body is provided with keepers 9 which are engaged by the clamps 10 on the bolts 11. The base is provided with upward offsets 12 slotted at 13 to receive the bolts, the offsets providing recesses 14 for the heads of the bolts as shown in Fig. III.

Thus arranged, the body and base may be securely clamped together. This may be done prior to lowering into the grave if desired, or the particular arrangement of clamps permits of their being engaged after the parts have been lowered into the grave.

The body is made air tight so that an air seal is provided preventing the entrance of water. It is not necessary to depend upon an air tight joint between the body and the base, although if desired this joint may be cemented.

Having thus described my invention what I claim as new and desire to secure by Letters Patent is:

1. In a grave vault, the combination of a cast iron base, a cast iron body resting on said base and comprising integral top, side and end walls and having a reinforcing rib at the edge thereof, the top having a centrally disposed longitudinal reinforcing rib, the ends and sides having reinforcing ribs extending from said edge reinforcing rib and merging into said top reinforcing rib, said top having hand holds projecting from its said reinforcing rib and laterally projecting keepers adjacent the edges thereof, said base being slotted at its edges to receive bolts, bolts engaged in said slots, and clamps on said bolts coacting with said keepers on said body.

2. In a grave vault, the combination of a cast iron base having an integral casket pedestal thereon, a cast iron body resting on said base and comprising integral top, side and end walls and having a reinforcing rib at the edge thereof, the top having a centrally disposed longitudinal reinforcing rib, the ends and sides having reinforcing ribs extending from said edge reinforcing rib and merging into said top reinforcing rib, said top having hand holds projecting from its said reinforcing rib.

3. In a grave vault, the combination of a base having an upwardly projecting flange in spaced relation to the edges thereof with cross pieces on the flange providing a casket pedestal, a body resting on said base at the outside of said flange, said base being slot-

2
ted at its edges to receive bolts, bolts engaged in said slots, clamps on said bolts, and keepers on said body coacting with said clamps.

5. 4. In a grave vault, the combination of a base having an upwardly projecting continuous flange in spaced relation to the edges thereof with cross pieces on the flange providing a casket pedestal, a body resting on said base at the outside of said flange and

comprising integral top, side and end walls, said base being slotted at its edges to receive bolts, keepers on said body aligned with said slots in said base, and bolts engaging said slots and keepers whereby the body is 15 clamped upon the base.

In witness whereof I have hereunto set my hand.

LEON GSCHWIND.
